(57) **CLAIM**

The ornamental design for a cupboard, as shown.

DESCRIPTION

FIG. 1 is a perspective view showing my new design;

FIG. 2 is an interior view with shelves thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is an interior view with an accessory thereof.

The interior shelves in FIGS. 2 and 8 are shown in broken lines for illustrative purposes only and form no part of the claimed design.
